HOLDING RACK FOR ELONGATED ARTICLES

Josiah Shepard, Chevy Chase, Md.

Application June 27, 1946, Serial No. 679,743

1 Claim. (Cl. 211—69)

1

This invention relates to a holding rack for the convenient and secure retention of pens, pencils, crayons and other elongated articles which are used by draftsmen, architects, artists and school children.

It is the object of the present invention to provide a holding rack for pens, pencils and the like, which is economical and rugged in construction and which is capable of wide distribution and use at a low cost, to provide an excellent advertising medium addressed to those who use a multiplicity of pens, pencils and the like, drafting or other instruments, dental tools, drills and other elongated articles.

It is a further object of the present invention to provide a rack for elongated articles which is adapted to rest upon a supporting surface with a high degree of frictional drag so that the rack does not slide easily along the surface and remains in the place where it is originally set. At the same time, the rack provides a stable support for the individual elongated articles which are disposed in parallelism thereon in clear view of the operator so that the selection of the desired one can be made with rapidity and accuracy in view of the segregated disposition of the individual items upon the rack above the level of the supporting surface whereby they are rendered easy to pick up and lay down.

It is a further object of the invention to provide a rack which may be formed entirely of sheet material of flexible, rigid or semi-rigid characteristics, or which alternatively may be formed in part of solid rests for the elongated articles. In the former case, the racks lend themselves to stacking capabilities for compact shipment and storage.

It is a further object of the invention to provide a rack which may be stamped out of sheet material in an economical manner with minimum waste. When white material is used for pencil or crayon racks of different colors, the individual rests of the rack may be identified with the different colors to designate the proper location of the respective crayons or pencils.

Furthermore, in accordance with the present invention the rack in its fully loaded position is capable of convenient lifting and carrying without disturbing the distribution of the elongated articles thereon so that the same may be put in a drawer and returned to the point of use at any desired time with rapidity and dispatch.

The invention proceeds upon the principle of providing a rack constituted of a pair of parallel triangularly-shaped prismatic elements spaced

2

laterally from each other and which are spanned by a base member adapted to be disposed in contact with the supporting surface on which the rack is placed. A plurality of notches are cut in the apex along the length of each prismatic element transversely thereof with the notches in each element in alignment with the corresponding notches in the adjacent element for the purpose of providing secure rests for the elongated articles which are bridged across the two prismatic elements. When the rack is formed of sheet material such as cardboard or pressboard, the base, in conjunction with the upstanding gable elements formed on each side thereof, provides sufficient frictional drag on the table on which the rack is disposed to maintain the rack in set position so that the artisan may at all times find the rack with the instrumentalities thereon in the position in which the same is placed originally, without occasioning any temporary loss of the instruments resulting from rolling or displacement thereof amongst papers or other items with which the operator may be working at the time.

25 The device is of particular utility for draftsmen working on an inclined board in which case the difficulties arising from rolling pens and pencils are always present. If desirable, the base of the rack may be provided with apertures for the purpose of affixing the rack permanently to any desired part of the drafting board.

Other objects and purposes will appear from the detailed description of the invention following hereinafter, taken in conjunction with the accompanying drawing, wherein

35 Fig. 1 is a perspective view of the rack in accordance with the present invention as used on a drafting board;

Fig. 2 is a plan view of a preferred embodiment of my invention;

40 Fig. 3 is a front elevation of Fig. 2;

Fig. 4 is a vertical sectional view along line 4—4 of Fig. 2;

Fig. 5 is a plan view of a second embodiment of the invention;

45 Fig. 6 is a front elevation of Fig. 5;

Fig. 7 is a vertical sectional view along line 7—7 of Fig. 5; and

Fig. 8 is a plan view showing the economies accruing from the stamping out of the holding rack of an H-configuration from sheet material.

In Fig. 1 of the drawing a drafting board T is shown having the rack R in accordance with the present invention disposed near one corner thereof, with pens and pencils P on the rack in posi-

tion to be grasped conveniently by the draftsman as the need for the individual instruments arises. The individual items are readily visible and are capable of convenient handling by virtue of the segregated but nevertheless aligned position of these items and their disposition above the level of the drafting board. The same advantages arise when the rack is used on an ordinary business desk, school desk or work table which may be used by business men, school children, dentists, tool workers or other artisans who may have need for different instruments at different times in the course of their work and who desire to have these conveniently at hand for selection for utilization.

The rack R is preferably formed of sheet material which may be of cardboard, plastic, metal or the like, which is stamped from a large sheet S (Fig. 8). To make economic use of the sheet material, the rack is formed of an H-configuration having vertical long sides or legs 11 and 12 and an intermediate bridging member 10 extending from the mid-portions of said sides and which serves as the base of the rack. Thereby only portion 38 in the sheet S may be considered as waste. Each of the vertical legs 11 and 12 is shaped to form triangular prismatic or gable-shaped elements with apexes 13 and 14. Scored lines 10a and 10b at the junctions of the base 10 with sides 11 or 12 facilitate a bending of the sides into a raised position so that the base may rest flatly on a support, while the reverse bending of the scored lines 13 and 14 along the longitudinal median of each of the long sides transforms the long sides into gable-shaped bodies having the apexes 13 and 14 and only their long edges in contact with the support. A plurality of notches 15 are cut into apex 13 along the prismatic element 11 which are preferably diamond-shaped. Similar notches 16 are cut in element 12 into the apex 14 in alignment with the notches 15. As shown in Figs. 2 and 8, the diamond-shaped openings 15 extending along the sides 11 and 12 have the short diagonals thereof coincide with the scored longitudinal median lines 13 and 14 and the long diagonals of each respective pair of openings in sides 11 and 12 are in alignment. Thus when sides 11 and 12 are bent along the scored lines 13 and 14, V-shaped notches are formed therein each providing for supporting edges for an end of the pencil, pen or other instrument, providing a secure rest therefor and presenting an improvement over the supports known heretofore having notches in a single plane of sheet material. The base 10 may be of the same length as the prismatic elements and I have found that sufficient drag is afforded by the base 10 of lesser length in conjunction with the terminals of the prismatic elements 11 and 12 to retain the rack in set position without undue freedom of movement. Thus a rack of H-configuration is preferred to utilize the sheet material with minimum waste. If desired, the base 10 may be provided with apertures 18 for the purpose of securing the rack to the board by means of thumb tacks or the like.

The base 10 lends itself to the application of printed matter so that the device may be used effectively as an advertising medium. Furthermore, additional refinements, such as colored markings, individual to the respective notches, may be used to educate children to the proper and systematic use of coloring crayons and habits of orderliness.

As shown in Fig. 3, the openings in the ends of the gable elements 11 provide convenient engag-

ing spaces for the middle and little fingers of both hands in order to remove the rack and the instrumentalities thereon from place to place, or for convenient disposition thereof in a drawer while awaiting repeated use of the rack and the articles thereon at some later time.

It is readily seen from an examination of Figs. 1 to 4, that a plurality of racks of sheet material may be conveniently stacked one above the other in a minimum amount of space, even when the rack is formed of inflexible sheet material such as metal or plastic.

While the invention in its preferred form contemplates the stamping of the complete rack from sheet material, at which time the boundaries as well as the holding notches can be cut out in a single operation, a highly useful and practical pen rack is attained when the triangular prismatic elements are of solid material such as wood or plastic, which may be finished according to different colors, for example, according to the color of a desk such as mahogany or walnut. This embodiment of the invention is shown in Figs. 5, 6 and 7, wherein the solid prismatic elements 21 and 22 are provided with aligned notches 25 and 26, respectively, and are bridged by a base member 20 which is affixed to the prismatic elements 21 and 22 by means of screws 29. Apertures 28 may be provided in the base 20 for the purpose of affixing the rack to a supporting surface, either permanently or temporarily.

Depressions or dimples 27 are provided in the ends of solid prismatic elements 21 and 22 in order to facilitate a secure holding of the rack between the fingers of both hands when it is desired to carry the rack with the contents thereon from place to place.

From the above description, it is readily seen that the invention contemplates a simple rack which is capable of mass production at an insignificant cost when the same is produced of cardboard, pressboard or the like, and the cost of which may be varied by the utilization of more expensive materials such as plastics, metal or wood, in order to cater to widely divergent markets.

While the advantages of my invention do not depend upon any specific size of the rack, I have found one having the following dimensions particularly desirable: length of each side 7" and 50 width 2" to allot 1" to each side of the triangular prisms, with six notches displaced 1" apart; and the base between the prisms being 3" long and 2" wide between the prisms.

While I have described my invention as embodied in a specific form and as operating in a specific manner for purposes of illustration, it should be understood that I do not limit my invention thereto, since various modifications will suggest themselves to those skilled in the art without departing from the spirit of my invention, the scope of which is set forth in the annexed claim.

I claim:

65 A blank of sheet material for forming a holding rack for pens, pencils or the like having an outline of the letter H adapted to be stamped from a larger sheet in which the blanks are interengaged and juxtaposed, said blank having opposed long sides bridged by a base member extending from the mid-portions of said long sides at scored lines between said sides and said base member, a plurality of diamond-shaped openings extending along the length of each side with the short diagonals of said openings coinciding with 70 the scored longitudinal median line of each long

side and with the long diagonals of each respective pair of openings on said long sides being in alignment, so that when said long sides are bent along their median lines to form gable-shaped bodies, V-shaped notches are formed therein to provide secure rests for elongated articles of all shapes, contours and sizes which are adapted to extend between said long sides, the scored lines along the longitudinal medians of said long sides adapted to be bent reversely to the scored lines 10 at the junctions of said base with said sides so that said base may rest flatly on a support while said sides of the gable-shaped bodies have only their long edges in contact with the support.
